UNITED STATES PATENT OFFICE.

PHILIP H. SUKERT, OF CHICAGO, ILLINOIS.

CIGAR-BOX MOISTENER AND COVER.

Application filed May 14, 1926. Serial No. 109,168.

This invention relates to attachments for cigar boxes and more particularly to a cigar box moistener and cover.

One of the main objects of the invention is to provide a device of the character stated of simple and efficient construction which can be readily applied and can be produced at comparatively small cost. A further object is to provide a device of this character so constructed that the moistener unit can be used either separately or in combination with a cover member, as desired. Another object is to provide simple and efficient means whereby a cover member of glass or other suitable transparent material can be readily replaced when necessary or desired. Further objects will appear from the detailed description.

In the drawings:

Fig. 1 is a perspective view of the device as applied.

Fig. 2 is a transverse sectional view through the device as applied, the cigar box being partly broken away and shown in section.

Fig. 3 is a perspective underneath view of the device.

Fig. 4 is a fragmentary perspective underneath view of a corner portion of the device, the cover member being omitted.

Fig. 5 is a section taken substantially on line 5—5 of Fig. 4.

The moistener device includes a box-like casing 1 of rectangular cross section formed of sheet metal and provided at each end with hook elements 2 extending rearwardly from rear wall 1^a of casing 1. These hook elements are disposed to fit about the end portions of lid *a* of a cigar box A of standard construction, thus providing simple and efficient means for attaching the device to the lid of the box. The casing is provided in its lower wall with a longitudinally extending slot 3 and a bottom wall 4 extending rearwardly from the front wall 1^b of the casing. The casing is further provided with end walls 5 separated from the back wall 1^a by slots 6. The casing constructed in this manner is adapted for reception of a strip 7 of absorbent material such as sponge, or other suitable material. This strip is dampened and, when the device is applied, air enters the casing through slot 6 in each end thereof and flows over the moistened strip of absorbent material so as to cause evaporation of the moisture contained there-

in. This evaporation causes cooling of the air resulting in a down current of moistened air which flows through the slot 3 into box A and serves to moisten the cigars contained in the box so as to prevent them from becoming dry and brittle.

The moistening device is intended for use in connection with a cover frame 8 of channel cross section which is open at its rearward side and is cut to provide upper tabs 9, side tabs 10 and lower tabs 11. This frame receives a closure member 12 of glass or other suitable transparent material which is inserted into the frame from the rearward side thereof. After this glass has been inserted it is secured in position by bending the tabs 10 inwardly so as to abut the rearward edge of the glass, as illustrated in Fig. 3. The bottom wall 4 is cut at each end to provide a securing tab 13. In initially assembling the complete structure the glass is inserted in the frame 8 and secured therein in the manner described, after which this frame is positioned so that the rearward ends of tabs 9 contact with the rearward wall 1^a of casing 1, the upper faces of the end arms of the frame being in contact with the under face of the bottom wall 4. The tabs 13 are then bent inwardly over the end arms of the frame, after which tabs 11 are bent upwardly so as to overlie tabs 13. This operation will be clear from Fig. 4. By bending the tabs in this manner the frame can be quickly secured to the casing 1 so as to form therewith a complete structure. If desired, the frame can first be secured to casing 1 after which the glass closure 12 can be inserted, as will be clear from Fig. 4, tabs 10 being then bent inwardly into the positions illustrated in Fig. 3. If it becomes necessary or desirable at any time to remove the closure 12 this can be readily accomplished by bending the tabs 10 outwardly as in Fig. 4. This permits the closure 12 to be withdrawn after which another closure can be inserted into the frame and secured in the manner previously described. It is also to be noted that the frame 8 can be readily detached from casing 1 if for any purpose this becomes desirable.

This device is applied to box A by inserting the lid *a* of the box into the hook members 2, moving the casing 1 downwardly along the lid until the frame 8 with its closure member 12 rests upon the upper edge of box A so as to form a closure therefor,

as in Figs. 1 and 2. When it is desired to open the box, cover A is tilted backwardly, raising the frame 8 and closure 12 permitting ready access to the box. As the frame 8 extends forwardly from the lower edge of the casing 1, the weight of this frame and the closure member carried thereby is sufficient to move the closure member into closed position by gravity when lid a is released.

When the closure member is in normal or lowered position the moisture from strip 7 flows downwardly through slot 3 into the box A at the back thereof, as will be clear from Fig. 2.

This invention is intended more particularly as an improvement over the device illustrated in my U. S. application for cigar box moistener, filed December 18, 1925, Serial No. 76,258. In the improved form described herein the glass closure member is effectually secured against casual displacement, and the parts are so associated that the closure structure can be detached from or secured to the moistener structure as desired.

What I claim is:

1. In a device of the character stated, a casing adapted for reception of an absorbent material and having an opening at its lower side, means for attaching the casing to a cigar box lid, a frame of channel construction open at one side and provided with tabs extending from said frame at the open side thereof, a closure member mounted in the frame, certain of said tabs acting to retain the closure member in the frame, and tabs carried by the casing and bent into interlocking relation with the retaining tabs of the frame and cooperating therewith for detachably securing the frame to the casing.

2. In a device of the class described, a casing comprising a front wall, a rear wall, and end walls separated from the rear wall by slots, said front wall having a flange portion extending transversely of the open bot-

tom of the casing to provide together with the rear wall a longitudinally extending slot, means for attaching the casing to a cigar box lid, an absorbent member confined in the casing and supported by said flange, in combination with a closure member, and means including a channel shaped frame for detachably securing said closure member to said casing.

3. In a cigar box moistener, a casing having end and bottom walls provided with communicating slots, means for slidably connecting the casing to a cigar box lid, and an absorbent member confined in said casing.

4. In a cigar box moistener, a casing having end and bottom walls provided with communicating slots, means for slidably connecting the casing to a cigar box lid, and an absorbent member confined in said casing, in combination with a closure member, and means including a channel shaped frame for detachably connecting the closure member to said casing.

5. In a cigar box moistener, a casing including a front and rear wall, and walls separated from the rear wall by slots in the end walls and a slot in the bottom wall of said casing, said rear wall having end portions bent back upon the rear wall to provide hooks adapted for slidable connection with the lid of the cigar box, a closure member, means providing connection between said closure member and said casing, and an absorbent member confined in said casing.

6. In a cigar box moistener, a casing including a front and rear wall, and walls separated from the rear wall by slots in the end walls and a slot in the bottom wall of said casing, said rear wall having end portions bent back upon the rear wall to provide hooks adapted for slidable connection with the lid of the cigar box, and an absorbent member confined in said casing.

In testimony whereof I affix my signature.

PHILIP H. SUKERT.
